AUTOMATIC SHOWER HEAD

James Fraser, Wilmington, Del., assignor to
The Speakman Company

Filed Feb. 20, 1958, Ser. No. 716,492

3 Claims. (Cl. 239—109)

The present invention relates to shower heads for use in shower baths, and more in particular to new and improved shower heads which are automatically self-cleaning in action.

Heretofore many shower heads have been provided with a manually operated handle which is connected to an adjustable water dispensing disk so that the disk may be raised or lowered to produce a spray and to clean the head when it is no longer being used.

Certain designs have incorporated a movable shower head so as to produce a self-cleaning head, that is one in which the spray producing device will move when the water pressure drops, thus cleaning the head automatically, but most of these devices have the shower producing skirt in the interior part of said shower head and force the same downwardly with increased water pressure into contact with the restricting disk across the opening thereof.

The present invention has for its object a shower head having the disk outside of the head and below the skirt and so arranged as to be mounted on a movable piston which is automatically raised by the water pressure so as to place the disk against the skirt in the shower producing position. This avoids the difficulties encountered in another type of shower head commonly in use which is manually adjusted by screwing the disk up against the skirt.

It is a further object of the present invention to provide a shower head that is self-cleaning, automatic in operation and has the skirt below the disk so as to allow visual determination of the operation thereof.

The various features of novelty which characterize this invention are pointed out with particularity in the claims annexed hereto and forming part of this application. For a better understanding of the invention its advantages and specific objects obtained by its use, reference should be had to the accompanying drawings and descriptive matter in which have been illustrated a preferred embodiment of the invention.

In the drawings:

Fig. 1 is a top fragmentary view of a shower head embodying this invention.

Fig. 2 is a side view of the shower head shown in Fig. 1.
Fig. 3 is a bottom view of the shower head.

Fig. 4 is a view, partially in section, through the shower head showing the first embodiment of this invention.

Fig. 5 is a sectional view on line 5—5 of Fig. 1.

Fig. 6 is similar to Fig. 4, showing the piston in the closed position.

Fig. 7 is a sectional view on line 7—7 of Fig. 4.

Fig. 8 is a sectional view through a shower head embodying the second modification of this invention.

Fig. 9 is a sectional view similar to Fig. 8, showing the piston in the closed position.

In the drawings, Figs. 1 to 7 inclusive illustrate the first embodiment of this invention. The shower head has

2

a casing 10 with a water supply inlet 11 in the upper end thereof having a knurled outer surface 12 and a threaded inner surface to facilitate connection to the source of supply, usually through a ball joint (not shown). This 5 casing has a disk 13 shown in Figs. 4, 5 and 6, mounted by means of screw threads 28 in the lower end thereof. Recesses 14, 14 to receive a wrench facilitate the mounting of this disk within the casing 10. This disk has a central opening 15 shown in Fig. 3 through which operates a piston 16, more clearly illustrated in Fig. 7. This piston has an enlarged machined portion 17, formed thereon which acts as a valve member and contacts the machined surface 29, shown in Fig. 6 of the disk 13 to form a closure when the piston is in the position shown in Figs. 10 15 and 5. This prevents the emission of water from the shower head. The piston 16 has a flange 18 mounted on the upper end thereof which fits within a cylinder 19 and is held in water-tight engagement therewith by the packing member 20. Mounted between the piston and 15 the head of the cylinder is a spring member 21 forcing the piston downwardly so as to force the enlarged portion of the piston into contact with the disk and maintain the assembly in water-tight engagement. In the lower part 20 of the cylinder are the openings 22, 22 forming a water passage between the space between the casing 10 and the cylinder 19 and allowing the water under pressure to flow in below the flange 18. Mounted on the lower end of the piston by means of the screw 23 is a skirt 24 of 25 smaller diameter than the flange 18. This skirt is provided with an annular series of grooves 25 or jet discharge passages as shown in Fig. 3. The screw 23 has the threaded portion 30 on the upper end thereof which is received by the thread 31 in the piston 16 so as to hold the skirt 24 in position and has a vent 26 through 30 the center of the screw and the center of the piston which vents the portion of the cylinder above the flange 18.

The modification shown in Figs. 8 and 9 is similar in construction to that shown in Figs. 1 to 7 inclusive except that there is no spring between the flange on the piston 40 and the top of the cylinder. There is a weight shown in Figs. 8 and 9 on top of this piston, which forces this piston downwardly as shown in Fig. 8 so as to close the enlarged portion of the piston into water-tight engagement with the machined edge of the disk 13, as shown in Fig. 8.

In operation the water is admitted through the water supply inlet 11 and flows around the cylinder 19 through the openings 22 and exerts a pressure against the lower part of the flange 18 which pressure is exerted against 50 the spring 21. When the pressure has increased to the point that it exceeds the pressure of the spring 21 the piston rises and allows the water to flow underneath the enlarged portion 17 and through the opening 15 and through the depressed openings 32 in the side of the piston 16, which are not milled as high as the enlarged portion 17. This also brings the skirt 24 into engagement with the side of the disk 13 and allows the water to flow through the jet grooves 25, shown in Fig. 3, thereby producing a spray, and said skirt will remain in this 55 position as long as the water pressure exceeds the spring pressure. These jet openings gradually become clogged with dirt and other deposits of lime, shale, etc. When the water pressure is shut off this allows the spring to force the piston downwardly and opens up the jet openings so that they are automatically cleaned of this deposit. The disk on the lower end of the piston moves downwardly on opening and allows the operator to visually determine if the shower head is functioning properly. It also allows the operator to manually clean the jet opening if necessary. This device also has the advantage of the piston seating against the disk 13 when 60 65 70 75 80 85 90 95

the piston is in the closed position and prevents the slow leakage of the water from the shower head.

The modification shown in Figs. 8 and 9 operates in the same manner as described above except that the piston is held in the open position by the weight 27, as shown in Fig. 8, on the top end of the piston which biasing action has to be overcome by the water pressure against the flange 18' in order to raise the piston within the cylinder 19, as shown in Fig. 9.

The invention having been described with specific details including two modifications thereof it is understood that the same is not to be limited thereby as changes may be made in the arrangements and proportions of the parts and elements and that equivalents may be substituted therefor, all without departing from the spirit and scope of the invention as set forth in the appended claims.

What is claimed is:

1. In a self-cleaning shower head, a casing having a water supply inlet and outlet therefor, a disk arranged across the outlet having a central opening therein, a movable piston arranged within this opening, said piston having a skirt on the lower end thereof, the upper end of said piston fitting within a cylinder and having biasing means within the cylinder above the piston, said cylinder being within said casing, vented through the piston, said piston having valve means thereon which contacts the upper surface of said disk when in the closed position and the skirt being beyond the disk when in the closed position, said piston being forced upwardly by the flow of water acting against biasing means within the cylinder and forcing the skirt into contact with the disk to produce shower producing sprays.

2. In a self cleaning shower head, a casing having a water supply inlet and outlet therefor, a disk arranged across the outlet having a central opening therein, a mov-

able piston arranged within this opening, said piston having a skirt on the lower end thereof, the upper end of said piston fitting within a cylinder and having biasing means within the cylinder above the piston, said cylinder being within said casing vented through the piston, said piston having valve means thereon which contacts the upper surface of said disk when in the closed position and the skirt being beyond the disk when in the closed position, said piston being forced upwardly by the flow of water acting against spring biasing means within the cylinder and forcing the skirt into contact with the disk to produce shower producing sprays.

3. In a self-cleaning shower head, a casing having a water supply inlet and outlet therefor, a disk arranged across the outlet having a central opening therein, a movable piston arranged within this opening, said piston having a skirt on the lower end thereof, the upper end of said piston fitting within a cylinder and having biasing means within the cylinder above the piston, said cylinder being within said casing vented through the piston, said piston having valve means thereon which contacts the upper surface of said disk when in the closed position and the skirt being beyond the disk when in the closed position, said piston being forced upwardly by the flow of water acting against weight biasing means within the cylinder and forcing the skirt into contact with the disk to produce shower producing sprays.
